ATTORNEY

UNITED STATES PATENT OFFICE.

WILLIAM C. STANKE, OF HOBOKEN, NEW JERSEY.

TOY.

Application filed October 4, 1920. Serial No. 414,466.

To all whom it may concern:

Be it known that I, WILLIAM C. STANKE, a citizen of the United States, residing at Hoboken, in the county of Hudson and State 5 of New Jersey, have invented new and useful Improvements in Toys, of which the following is a specification.

This invention relates to toys, and one of the principal objects is to provide a toy 10 which shall be both interesting to a child and a patriotic inspiration.

Another object is to produce a toy battleship which when moved across the floor will give a life-like imitation of a ship riding 15 up and down the waves.

Another object is to provide means whereby the figure of the ship may be advanced more rapidly when apparently riding down a wave than when it appears to be riding up.

With these and incidental objects in view, 20 the invention comprises certain novel construction and combination and arrangement of parts, the essential features of which are hereinafter described and claimed, and fully 25 illustrated in the accompanying drawing, in which:—

Figure 1 is a side elevation of my improved toy, showing the foremost position in full lines.

Figure 2 is a vertical sectional view of 30 the device on line 2—2, Figure 1, with the boat figure made from a piece of board or other flat material.

Figure 3 is a view similar to Figure 2 but 35 showing the boat figure as shaped up into proper relative thickness.

Figure 4 is a side elevation, showing several of the toys hitched together in squadron formation.

Figure 5 is a detail of the securing means 40 for the fulcrum pin.

Like characters of reference refer to like parts in all views.

Referring to the drawing in detail, 45 10 represents a box-like structure having depending sides 11 to cover the greater portion of the wheels, and preferably painted to simulate water. The box is also provided with a top portion 12 having a longitudinal

50 aperture 13 therein. Depending from member 12 are supports 14 which have at their lower ends bearings for front and rear shafts 15 and 16, the rear shaft 16 being formed with cranks 17 and a crank pin 18

55 At opposite ends, shafts 15 and 16 carry

wheels 19 projecting slightly below the sides 11.

A boat figure or form is shown at 20 and may be made either flat as shown in Figure 2 or shaped as shown in Figure 3, and in 60 either case is provided on its under side with a notch or cut away portion 21 extending in front and rear of the middle of the boat. It is, of course, understood that the boat figure may be made to simulate a battleship, 65 cruiser, torpedo-boat or anything of the like nature according to the desire of the maker.

The stern of the boat 20 is mounted upon the crank pin 18 so as to be given a rotary motion upon the revolving of the rear 70 wheels. A pin 22 is secured to the under side of member 12 and crosswise of aperture 13, and is held in place by thin metal strips 23. This pin 22 passes through the notch 21 and a thin strip 24 passes lengthwise of 75 notch 21 and is secured to the bottom of the boat so as to prevent disassociation of said pin and notch.

Pieces of quarter-round 25 are formed to simulate waves, and are suitably painted, 80 said pieces being mounted on the members 12.

If desired a series of toys may be secured together by U-shaped coupling hooks 25, the opposite ends of which are inserted into 85 apertures in adjacent ends of contiguous boxes 10. If it is desired to connect the boats beside each other or in staggered relation, the couplings should be inserted in the end of one box and the side of the adjacent one. 90

In operation, the toy is drawn along the floor and the rear wheels will cause the crank shaft 16 to effect a forward and backward movement of the boat figure and also, 95 the boat will rock about pin 22 so as to give an up and down movement. A boat at sea rides down a wave more rapidly than it mounts a wave and this effect is produced in the toy by the fact that the downward and 100 forward movement of the prow of the boat figure 20 accompanies the forward movement of the entire toy along the floor, whereas the upward movement of the prow is accompanied by a rearward movement of the 105 boat figure in the frame 10, so that the forward movement of the figure 20 is equal to the distance traversed by the wheels less the distance the figure 10 is moved rearwardly by the crank shaft. 110

Particular emphasis is laid upon the fact that this toy tends to arouse patriotic interest in our Navy in the minds of the children using the same.

5 While I have described what I deem to be the most desirable embodiment of my invention it is obvious that many of the details may be varied without in any way departing from the spirit of my invention; and I
10 therefore do not limit myself to the exact details of construction herein set forth nor to anything less than the whole of my invention limited only by the appended claims.

What is claimed as new is:-

15 1. In a device of the class described, the combination of a box-like frame having an aperture therein, a pin extending crosswise of said aperture, a boat figure provided with a cutaway portion for co-action with said pin, wave-simulating members mounted adjacent to said aperture, means for securing said pin and figure in co-operative relationship, wheels upon which said frame is supported, and a crank shaft operable by cer-

tain of said wheels and secured to said 25 figure.

2. In a device of the class described, the combination of a framework, wheels upon which said framework is supported, a crank shaft operable by certain of said wheels, a 30 pin stationarily mounted on said framework, and a boat figure secured slidably on said pin and operable by said crank shaft for effecting sliding and rocking movement of said boat figure on said pin. 35

3. A toy comprising a wheeled frame simulating a body of water, a boat structure freely embraced by said frame, means securing said body to said frame and permitting sliding movement of said body relatively to said frame, and a crank-shaft supported by said frame and connected to said body and operable to move said body on the first said means to effect sliding and rocking movements of said body. 40

In testimony whereof I have affixed my signature.

WILLIAM C. STANKE.
